UNITED STATES PATENT OFFICE

2,462,426

PREPARATION OF POLYALKYLBENZYL PHENOLS

Orland M. Reiff, Woodbury, and Howard D. Hartough, Pitman, N. J., assignors to Socony-Vacuum Oil Company, Incorporated, a corporation of New York

No Drawing. Application September 14, 1944,
Serial No. 554,163

8 Claims. (Cl. 252—52)

1

The present invention relates to the preparation of mono- and poly- (polyalkylaralkyl) monohydric and polyhydric mononuclear and polynuclear phenols and more particularly to the preparation of polymethyl benzyl monohydric and polyhydric mononuclear and polynuclear phenols.

Those skilled in the art are aware that some alkylated phenolic compounds have an excellent stabilizing action upon hydrocarbon oils. However, it has been shown in United States Patent No. 2,202,877 that the stabilizing action of alkylated phenols depends upon the type of alkyl groups introduced in the alkylation process and upon the position of the preferred alkyl groups on the phenolic nucleus. For example, the disclosure of the aforementioned United States Patent teaches that 2,4,6-trimethyl phenol is not nearly so effective a stabilizer for hydrocarbon oils as is 2,6-di-tertiary-butyl para cresol (2,6-di-tertiary butyl,4-methyl phenol) and that 2,4-di-tertiary butyl meta or ortho cresol are much less effective than the latter.

It has now been discovered that polyalkylbenzyl monohydric and polyhydric mononuclear and polynuclear phenols have a stabilizing effect upon hydrocarbon oils.

It is an object of the present invention to provide a process for preparing mono- and poly- (polyalkylaralkyl) monohydric and polyhydric, mononuclear and polynuclear phenols. It is another object of the present invention to prepare phenols of the aforesaid class from phenolic compounds and halogenated aromatic compounds obtained from petroleum oil. It is a further object of the present invention to provide a method for producing mono- and poly- (polyalkylbenzyl) monohydric and polyhydric mono- and polynuclear phenols. The present invention likewise contemplates the production of stabilized hydrocarbon oils containing small but effective amounts of at least one of the aforesaid mono- and poly- (polyalkylaralkyl) mono- and polyhydric mono- and polynuclear phenols. Other objects and advantages will become apparent from the following description.

As has been disclosed in the copending application Serial No. 515,145 filed December 21, 1943, in the name of Howard D. Hartough certain fractions of petroleum oil and particularly fractions of petroleum oil which have been subjected to cracking conditions contain alkylated mono- and polynuclear aromatic hydrocarbons. A fraction of cracked oil having a boiling range of about 155° C. to about 200° C. is available com-

2

mercially. This fraction consists essentially of polyalkylated benzenes mixed with non-aromatic, i. e. acyclic and alicyclic hydrocarbons. For the purpose of illustrating, but not limiting the present invention, the preparation of mono- and poly- (polyalkylaralkyl), mono- and polyhydric, mono- and polynuclear phenols will be described in conjunction with the use of this fraction as one of the components of the reaction.

10 As has been described in the copending application, Serial No. 515,145 filed December 21, 1943, in the name of Howard D. Hartough the polyalkylbenzyl chlorides employed in the process of the present invention may be produced from aromatic petroleum stocks containing a relatively high percentage of aromatic hydrocarbon constituents such as stocks derived from Houdry cracking operations and commercial operations.

15 The aromatic hydrocarbons that occur in such stocks are believed to be primarily polymethyl benzenes ranging from trimethyl benzene to tetramethyl benzene. It is possible that small amounts of other aromatic hydrocarbons, such as ethylmethyl benzene may be present also. There are three trimethyl benzenes, mesitylene or 1,3,5-trimethyl benzene; pseudocumene or 1,2,4-trimethyl benzene; and hemimellitene or 1,2,3-trimethyl benzene. Likewise, there are three tetramethyl benzenes, durene or 1,2,4,5-tetramethyl benzene; isodurene or 1,2,3,5-tetramethyl benzene; and prehnitene or 1,2,3,4-tetramethyl benzene. The trimethyl benzenes constitute the predominant portion of the polyalkylated benzenes present in stocks such as those to which reference is made hereinbefore. For example, if a stock of the type described hereinbefore and having a boiling range of about 155° C. to about 200° C. and containing 55 per cent aromatic hydrocarbons, is subjected to distillation, the fraction boiling between 150° C. and 182° C. will contain 60 per cent aromatic hydrocarbons and will constitute 75 per cent of the original "Sovasol" #75 stock. This temperature range (150° C.—182° C.) includes the boiling points 20 of the trimethyl benzenes, but does not include the boiling points of the tetramethyl benzenes. Stated differently, the 75 per cent distillate contains about 82 per cent of the aromatic hydrocarbons originally present in the stock having a 25 boiling range of about 155° C. to about 200° C. that boil within the boiling range of trimethyl benzenes.

30 The polyalkylaralkyl chlorides employed in the condensation reaction of the present invention may be produced in the following manner illus-

trated by the preparation of methylbenzyl chlorides from a hereinbefore described stock having a boiling range of about 155° C. to about 200° C. The aforescribed aromatic petroleum stock is mixed with any alkyl aldehyde such as formaldehyde, acetaldehyde, etc., in the proportion of 1000 grams of the aforesaid aromatic petroleum stock to about 165 to about 330 grams of 37 per cent formalin solution. About 825 cc. to about 1600 cc. of concentrated hydrochloric acid are added to the aromatic petroleum stock-formalin mixture and a stream of hydrogen chloride passed through the mixture. The temperature is maintained between about 60° C. and about 70° C. for about 6 hours. At the end of the period agitation is stopped and an aqueous layer separated. The hydrocarbon layer is thoroughly washed with water to remove excess hydrochloric acid and aldehyde. The hydrocarbon layer is dried, preferably over calcium chloride and fractionated, the portion distilling over at 110° C. to 130° C. at 10 millimeters pressure being a mixture of chloromethylated aromatic hydrocarbons or polyalkylbenzyl chlorides. The still residue contains dichloromethylated compounds. These polyalkylbenzyl chlorides are then reacted with mono- or polyhydric, mono- or polynuclear phenols or mixtures thereof to produce the mono- and poly- (polyalkylaralkyl) monohydric and polyhydric, mono- and polynuclear phenols of this invention. So far as we are aware no one has prepared alkylated phenolic compounds by the condensation of phenol, polyhydric phenols or polynuclear phenols such as naphthols with polyalkylbenzyl chlorides obtained from petroleum oil.

Furthermore, we have found that the conditions under which the condensation of the phenol and the polyalkylaralkyl halide takes place has a marked effect upon the properties of the reaction product. The solubility in hydrocarbon oils of lubricating range appears to be dependent upon the method of preparation and the stabilizing effect of the products apparently differs in accordance with the method of preparation. Thus, when the reaction is carried out in the presence of an inert solvent the effectiveness of the product as a stabilizer for hydrocarbon oils is impaired or substantially destroyed.

The production of mono- and poly- (polyalkylaralkyl) mono- and polynuclear and mono- and polyhydric phenols will be illustrated first and then the effect of the conditions under which the condensation takes place will be described.

EXAMPLE I

Mono-(polyalkylbenzyl) phenol

One hundred and ninety three (193) grams (1.1 moles) of polyalkylbenzyl chlorides from aromatic petroleum stock having a boiling range of about 155° C. to about 200° C. and 180 grams (1.9 moles) of phenol were added to 400 milliliters of xylene. After standing at room temperature (15° C.-35° C.) for a few minutes hydrogen chloride was evolved. The temperature was raised slowly to the temperature at which xylene refluxed (135° C. to 140° C.) and held at this temperature for six hours. Excess phenol and traces of chlorine preferably are then removed. This can readily be accomplished by cooling the reaction mixture, adding a small amount of zinc dust and refluxing the mixture for a short time to remove the last traces of chlorine from the product. The excess phenol preferably can be removed by filtering the substantially chlorine

free reaction product and washing the filtrate with dilute aqueous soda ash solution. The xylene was removed by distillation and a light brown oily residue recovered. This residue was subjected to distillation in a vacuum. A portion of this residue boiling at 200° C. to 225° C. at 10 millimeters of mercury was recovered in the amount of 180 grams and found to be a mixture of ortho and para mono-(polyalkylbenzyl) phenol. An undistillable residue of 50 grams of polybenzylated phenol was also obtained. The 180 grams of ortho and para mono-(polyalkylbenzyl) phenol represents 80 per cent of theoretical based on the amount of phenol used.

EXAMPLE II

Di-(polyalkylbenzyl) resorcinol

Thirty grams (0.27 mole) of resorcinol were dissolved in 100 milliliters of xylene and 85 grams (0.50 mole) of polyalkylbenzyl chlorides from aromatic petroleum stock having a boiling range of about 155° C. to about 200° C. were added. The mixture was heated to the reflux temperature of the solvent (135° C. to 145° C.) and held at that temperature for about three hours. When desirable, traces of chlorine may be removed, as is preferred, by adding one gram of zinc dust and refluxing the material for about 0.5 hour longer. The mixture was then filtered, water-washed and solvent removed. A dark red, brittle, resinous material was obtained. This resinous material was decidedly more soluble in hydrocarbon oils than the reaction product obtained in the next example.

Those skilled in the art will understand from the foregoing that to obtain mono-substituted phenols the polyalkylaralkyl halides are reacted with the phenols in the proportion of about 1.1 moles of the former to about 1.9 moles of the phenol. In other words, the halide is reacted with an excess of phenol to produce the mono-substituted phenol; the halides and the phenol are reacted in about stoichiometric proportion to produce the di-substituted phenol.

Illustrative of the effect of carrying out the reaction in the absence of a solvent is the following procedure in which the polyalkylaralkyl halides and the phenol were reacted in the proportion to produce a di-substituted phenol. That is to say, in the proportion of 0.51 mole of phenol to 1.02 moles of polyalkylaralkyl halide.

EXAMPLE III

Twenty-four grams (0.255 mole) of phenol were added to 87 grams (0.51 mole) of polyalkylbenzyl chlorides from aromatic petroleum stock having a boiling range of about 155° C. to about 200° C. The mixture was slowly heated to about 125° C. and held at that temperature until the evolution of hydrogen chloride had ceased. This normally requires about 3 to about 5 hours. In other words, the mixture is slowly heated at least to a temperature at which the reaction takes place as evidenced by the evolution of hydrogen halide and held at that temperature until the reaction is substantially complete as indicated by the cessation of the evolution of hydrogen halide. This temperature varies for different phenols and different polyalkylaralkyl halides but is normally between about 50° C. and about 125° C. After the evolution of hydrogen halide has ceased it is preferred to remove traces of halide by adding a small amount of zinc dust. Accordingly, after the reaction mixture had cooled one gram of zinc dust was added and the mixture refluxed for

0.5 hour longer. After cooling, benzene was added to the product in amount sufficient to dissolve the reaction product. The zinc dust was separated from the benzene solution and the benzene solution of the product water-washed until substantially free from the phenol. Four washings are usually sufficient. After water-washing the benzene was removed by distillation and a resinous product was obtained which had good color and which was found to be soluble in hydrocarbon oils in concentrations as high as 0.5 per cent.

Mono- and poly- (polyalkylaralkyl) derivatives of mono- and polyhydric mono- and poly-nuclear phenols may be prepared by means within the scope of this disclosure. Among the compounds prepared in accordance with the foregoing disclosure were the following:

- a. Mono-(polyalkylbenzyl) phenol
- b. Di-(polyalkylbenzyl) phenol
- c. Tri-(polyalkylbenzyl) phenol
- d. Di-(polyalkylbenzyl) o-cresol
- e. Di-(polyalkylbenzyl) m-cresol
- f. Di-(polyalkylbenzyl) p-cresol
- g. Di-(polyalkylbenzyl) resorcinol
- h. Di-(polyalkylbenzyl) catechol
- i. Di-(polyalkylbenzyl) hydroquinone
- j. Di-(polyalkylbenzyl) pyrogallol
- k. Di-(polyalkylbenzyl) α -naphthol

Those skilled in the art will understand that the products produced by carrying out the reaction between the polyalkylaralkyl halides and the phenol in the absence of a solvent or diluent probably contain some more highly condensed materials than do the products of the same reaction when carried out in the presence of a solvent or diluent. However, since the former products are more effective as stabilizers the production thereof is particularly important. Accordingly, wherever the product of the reaction carried out in the presence of a diluent or solvent is discussed the product will be designated as the

product of the reaction between about 1 mole of polyalkylbenzyl chloride and about 1 mole of phenol in the presence of a solvent will be designated as "monobenzyl phenol." That product resulting from the reaction between about 1 mole of benzylchlorides and about 0.5 mole of phenol in the presence of a solvent will be designated as "dibenzyl phenol."

Various of the phenols and reaction products were subjected to various tests to determine the stabilizing effect of the phenol or the reaction product upon acid refined oil of the lubricating grade and upon solvent refined oil of the lubricating type. The general knowledge of the art was confirmed, to wit: that some stabilizers are more effective in acid refined oil than in solvent refined oil. However, it was surprising to find that some of the products of this invention were apparently equally effective in both acid refined and solvent refined oil as determined by an accelerated test simulating the conditions encountered in turbine operation. This test involves subjecting samples of oil and samples of the same oil containing various amounts of various stabilizing agents to the effect of air bubbled through the oil samples in the presence of moisture, iron and copper while the oil samples are maintained at an elevated temperature of say about 200° F. The amount of sludge produced after different intervals of time is determined. The amount of sludge produced is an indication of the stabilizing effect of the added material. The less sludge produced in a given period of time as compared to the amount produced in the control for a given interval of time the better the stabilizing value of the added material. The tests, the results of which are tabulated herein-after, were performed employing acid and solvent refined turbine oils of 150 Saybolt second viscosity at 100° F. For purposes of comparison the stabilizing effect of 2, 6-di-tertiary butyl, 4-methyl phenol disclosed in U. S. Patent No. 2,202,877 to be extremely satisfactory has been included in these data.

Table I

Additive	Percent conc.	H ₂ SO ₄ refined oil					Solvent refined oil		
		Hours on test	N. N.	Mg sludge	KNN ¹	K sludge ²	Hours on test	N. N.	Mg sludge
Control									
2,6-di-tertiary butyl, 4-methyl phenol	0.2	336	16.0	1,282			166	8.3	59
"Dibenzyl catechol"	0.2	695	2.1	23	16	95	615	12.6	89
"Dibenzyl phenol reaction product"	0.2	1,728	5.8	322	14	20	1,728	0.9	38
"Dibenzyl resorcinol"	0.2	2,040	0.9	106	109	73	1,171	8.0	150
"Dibenzyl p-cresol reaction product"	0.2	3,017	4.1	246	35	36	2,890	13.2	93
"Dibenzyl resorcinol reaction product"	0.2	2,210	0.9	107	171	114	1,732	22	
		5,760	2.2	134	121	171	2,688	19.0	110

¹ KNN = $\frac{\text{NN of control} - \text{NN of test blend}}{\text{NN of test blend}} \times \text{hrs. on test for test oil}$

² K sludge = $\frac{\text{mg. sludge control} - \text{mg. sludge test blend}}{\text{mg. sludge test blend}} \times \text{hrs. on test for control}$

mono- or poly- (polyalkylaralkyl) phenol of the polyalkylaralkyl chloride. Thus, the product produced by reacting about 1 mole of polyalkylbenzyl chloride with about 0.5 mole of phenol in the absence of a solvent or diluent will be designated the "dibenzyl phenol reaction product" and the product of the reaction between about 1 mole of polyalkylbenzyl chlorides and about 1 mole of phenol in the absence of a solvent or diluent will be designated as the "monobenzyl phenol reaction product." On the other hand, the products of the reaction carried out in the presence of a diluent or solvent will be designated as the particular phenol produced. Thus, the prod-

Table II

2, 6-di-tertiary butyl, 4-methyl phenol	95
"Dibenzyl cathechol"	20
"Dibenzyl resorcinol"	36
"Dibenzyl phenol reaction product"	73
"Dibenzyl p-cresol reaction product"	114
"Dibenzyl resorcinol reaction product"	171

The foregoing tabulation clearly shows that the reaction products produced when the condensation reaction is carried out in the absence of a diluent are more effective stabilizers than the products obtained when an inert solvent is used. This tabulation also shows that under the condi-

8

The data provided hereinbefore makes it manifest that polyalkylbenzyl mono- and polyhydric phenols are satisfactory stabilizers for both acid refined and solvent refined oil, particularly turbine oils.

The products produced by condensation of polyalkylbenzyl chlorides with various mono- and polynuclear, mono- and polyhydric phenols in the presence of an inert solvent include the following 10 which have been subjected to the simulated turbine test described hereinbefore employing acid refined and solvent refined turbine oils of 150 Saybolt second viscosity at 100° F. with the results tabulated hereinafter in Table V.

Table V

Material	Percent conc.	H ₂ SO ₄ refined oil			Solvent refined oil		
		Hours tested	N. N.	Mg sludge	Hours tested	N. N.	Mg sludge
Monobenzyl phenol	0.2	312	1.3	21	605	2.9	462
Dibenzyl phenol	0.2	328	3.0	40	328	0.08	5
Tribenzyl phenol	0.2	331	2.6	32	403	1.1	12
Dibenzyl o-cresol	0.2	330	3.0	60	330	1.4	16
Dibenzyl m-cresol	0.2	306	1.5	12	306	2.1	23
Dibenzyl hydroquinone	0.2	236	1.6	17	2256	4.5	422
Dibenzyl pyrogallol	0.2	474	1.1	26	546	7.0	184
Dibenzyl naphthol	0.2	375	2.1	22	501	1.7	3

tions of this test the "dibenzyl resorcinol reaction product" is about 70 per cent more effective than 2,6-di-tertiary butyl, 4-methyl phenol in protecting acid refined oil.

When these additives are evaluated in the same manner for solvent refined oil the order of effectiveness is as follows:

Table III

2, 6-di-tertiary butyl, 4-methyl phenol	3
"Dibenzyl phenol reaction product"	3 (2.8)
"Dibenzyl resorcinol reaction product"	9
"Dibenzyl resorcinol"	11
"Dibenzyl catechol"	16
"Dibenzyl p-cresol reaction product"	23

The foregoing tabulation clearly shows that the "dibenzyl phenol reaction product" has about the same protective value for solvent refined oil as 45 2, 6-di-tertiary butyl, 4-methyl phenol and that the polyhydric phenols are more effective stabilizers in solvent refined oil than the 2, 6-di-tertiary butyl, 4-methyl phenol when evaluated by this method.

The following tabulation indicates that "dibenzyl p-cresol reaction product" and "dibenzyl resorcinol reaction product" are the most effective stabilizers for acid refined oil while "dibenzyl p-cresol reaction product" and "dibenzyl catechol" are the most effective for solvent refined oil being about nine and five times as effective, respectively, as 2,6-di-tertiary butyl, 4-methyl phenol.

Table IV

	H ₂ SO ₄ Refined		Solvent Refined	
	N. N.	Sludge	N. N.	Sludge
1 2,6-di-tertiary butyl, 4-methyl phenol	16	95	3	3
2 "Dibenzyl catechol"	14	20	96	16
3 "Dibenzyl resorcinol"	35	36	11	11
4 "Dibenzyl phenol reaction product"	109	73	7	3
5 "Dibenzyl resorcinol reaction product"	121	171	7	9
6 "Dibenzyl p-cresol reaction product"	171	114	-----	28

30 Although the present invention has been described in terms of the condensation of certain mono- and polynuclear, mono- and polyhydric phenols with polyalkylbenzyl chlorides derived from a particular fraction of aromatic petroleum stock, other polyalkylaralkyl chlorides may be used as well as other phenols as those skilled in the art will understand. Therefore the condensations described hereinbefore are to be considered illustrative of analogous condensations which may be made employing other aralkyl chlorides and other phenols.

We claim:

1. Hydrocarbon oil containing a small proportion, sufficient to stabilize said oil against deterioration from oxidation, of the reaction product obtained by reacting polyalkylaralkyl halides with a phenol in the molal ratio of about 1 to about 2 to about 2 to about 1 at elevated temperatures in the absence of a solvent.

2. Hydrocarbon oil containing a small proportion, sufficient to stabilize said oil against deterioration from oxidation, of a reaction product obtained by reacting about 0.27 mole of resorcinol with about 0.50 mole of polyalkylbenzyl chlorides at 125 degrees centigrade in the absence of a solvent until evolution of hydrogen chloride is no longer detectable.

3. Hydrocarbon oil containing a small proportion, sufficient to stabilize said oil against deterioration from oxidation, of a reaction product obtained by reacting about 0.27 mole of catechol with about 0.50 mole of polyalkylbenzyl chlorides at 125 degrees centigrade in the absence of a solvent until the evolution of hydrogen chloride is no longer detectable.

4. Acid refined petroleum oil containing a small proportion, sufficient to stabilize said oil against deterioration from oxidation, of a reaction product obtained by reacting about 0.27 mole of resorcinol with about 0.50 mole of polyalkylbenzyl halides at 125 degrees centigrade in the absence of a solvent until the evolution of hydrogen halide is no longer detectable.

5. Refined petroleum oil containing a small proportion, sufficient to stabilize said oil against

deterioration from oxidation, of dibenzyl p-cresol reaction product obtained by reacting p-cresol and polyalkylbenzyl halides in the molal ratio of about 1 to about 2 at elevated temperatures in the absence of a diluent.

6. Acid refined petroleum oil containing about 0.2 per cent by weight of dibenzyl resorcinol reaction product obtained by reacting resorcinol and polyalkylbenzyl halides in the molal ratio of about 1 to about 2 at a temperature of about 10 125° C. in the absence of a diluent.

7. Refined petroleum oil containing about 0.2 per cent by weight of dibenzyl p-cresol reaction product obtained by reacting p-cresol and poly-alkylbenzyl halides in the molal ratio of about 15 1 to about 2 at elevated temperatures in the absence of a diluent.

8. Refined petroleum oil containing a small proportion, sufficient to stabilize said oil against deterioration from oxidation, of a reaction prod- 20

uct obtainable by reacting polyalkylbenzyl halides and a polyhydroxyphenol in the molal proportions of about 1 to about 2 to about 2 to about 1 at elevated temperatures in the absence of a diluent.
